CLAIM

The ornamental design for a pet treat, as shown and described.

DESCRIPTION

FIG. 1 is a top front perspective view of a pet treat according to our new design;

FIG. 2 is a top plan view thereof;

FIG. 3 is a bottom plan view thereof; and,

FIG. 4 is a front elevational view thereof, with rear, right and left side elevational views being the same.

(Continued)

The stippled shading shown in FIGS. 1 and 2 illustrates a contrasting appearance for a filling portion of the pet treat.

1 Claim, 4 Drawing Sheets
